UNITED STATES PATENT OFFICE.

NATHANIEL TYLER, JR., AND WILLIAM A. LIEBER, OF WASHINGTON,
DISTRICT OF COLUMBIA; SAID LIEBER ASSIGNOR TO SAID TYLER.

DEVICE FOR HOLDING AND PRESSING TROUSERS.

SPECIFICATION forming part of Letters Patent No. 596,034, dated December 21, 1897.

Application filed May 19, 1897. Serial No. 637,251. (No model.)

To all whom it may concern:

Be it known that we, NATHANIEL TYLER, Jr., and WILLIAM A. LIEBER, citizens of the United States, residing at Washington, in the 5 District of Columbia, have invented certain new and useful Improvements in Devices for Holding and Pressing Trousers; and we do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

This invention relates to certain new and useful improvements in devices for holding and pressing trousers or other articles, and especially to means whereby a number of 20 pairs of trousers may be folded over rounds in a suitable framework, which rounds are so disposed with relation to one another that when a pair of trousers is folded over each of the various rounds the outer folds of each 25 pair will be substantially in the same plane—that is to say, the lower rounds, between which and the pressing-board there will be the greatest thickness of folds of overlapping trousers or other articles which it will be desired to 30 press, will be mounted in the side strips of the framework the farthest back from the front or pressing side of the device, while the upper round will be the nearest to the front side, with the intervening rounds set slightly back 35 of one another.

A further part of our invention resides in the provision of a suitable pressing-board which will hold the overlapping trousers or other articles in a compressed relation, thus 40 taking out any wrinkles and keeping the proper shape to the same, the compressing-board being preferably held to the framework by means of spring-clamps, which will cause an equal pressure to be applied the entire 45 length of the frame.

In connection with the foregoing it is our purpose to construct our improved garment pressing and shaping device so that it will "knock down" and be made to occupy a 50 small space, adapting it convenient for transportation by packing it in a suitable travel-

ing-case, it being our design to attach it to the side of a door, to which it may be held by suitable thumb-screws.

Another part of the invention resides in the 55 provision of means whereby any one pair of trousers folded over a round may be removed by simply removing the particular round desired without disturbing any of the other pairs which may be held within the pressing-frame, there being suitable fasteners to hold each round in place when they are inserted in the holes in the side strips of the frame.

Our invention is clearly illustrated in the 60 accompanying drawings, which, with the letters of reference marked thereon, form a part of this application, and in which drawings similar letters of reference indicate like parts throughout the several views, in which—

Figure 1 is a perspective view of our improved trousers-pressing frame, showing the pressing-board clamped to the framework, a portion of the board being broken away and a round partially removed. Fig. 2 is a view showing the frame knocked down in readiness to be packed for transportation. Fig. 3 is a central vertical sectional view through the pressing-frame and trousers being pressed therein. Fig. 4 is a sectional view through the frame on line 4-4 of Fig. 1. Fig. 5 is a 70 modified form of pressing-frame. Fig. 6 is a 75 sectional view on line 6-6 of Fig. 5. Fig. 7 is a 80 sectional detail view through one of the dovetailed corners.

Reference now being had to the details of 85 the drawings by letter, A designates a door or wall to which the pressing-frame is to be attached. The framework is composed of the strip B, which has suitable thumb-screws B' passing through the strip and which are 90 designed to engage in the side of the door or wall to hold the device thereto. To said strip B is hinged the lower portion C of the frame, which has its ends dovetailed to the upright strips D, which side strips have a similar 95 dovetailed connection with the top piece E, and at each corner of the frame is a retaining thumb-screw F, which thumb-screws may engage with threaded washers on the inner sides of the strips, as shown in the detail view, 100 Fig. 7.

One of the side strips D has a series of ap-

ertures d , (shown clearly in Fig. 4,) while the other strip on the opposite side has a series of depressions extending only partially through the strip, as seen in d' in Fig. 4 and also in Fig. 1. These apertures and holes or depressions are provided to receive the rounds G , adapting them to be removed. Over each aperture d is provided a pivoted spring retaining member D' , which when turned over the aperture, after the round has been adjusted in place, will hold the same in position.

It will be noted that the series of apertures d and the holes or depressions d' are disposed in inclined rows longitudinally in the side strips, so that when the trousers K are folded and placed on the rounds the outer folds of the various pairs will lie in substantially the same plane, so as to be equally pressed by the clamping-board M , which is held in place in a pressing relation against the overlapping pairs of trousers by means of the spring-clamps M' , which are pivoted to the board, as shown in Fig. 1 of the drawings, on the pins m , these spring-clamps engaging with the clips N . A suitable chain Q is attached at one end to the upper strip E , as at e , and when it is desired to swing the framework back against a door or wall one of the links of the chain may be caught over the hook S , as shown plainly in Figs. 1 and 3 of the drawings.

In Fig. 5 we have shown a slight modification in which the rounds are held in inclined grooves instead of the manner hereinbefore described, this construction making it convenient to remove any particular pair of trousers without first removing the round, as is necessary in the construction shown in Figs. 1 and 3.

We do not confine our invention to the precise construction shown and described, but may make slight alterations without departing from the spirit of the invention.

Having thus described our invention, what

we claim to be new, and desire to secure by Letters Patent, is—

45

1. A device for pressing trousers consisting of a suitable framework, supporting-bars held therein, and a board designed to be held under pressure against the overlapping folds of trousers held on said bars, substantially as set forth.

2. A device for pressing trousers, comprising a framework having a series of removable rounds mounted therein and in vertical parallel planes, combined with a detachable pressing-board and spring-clamps pivoted thereto, substantially as shown and described.

55

3. As an improved article of manufacture a device for holding and pressing trousers, comprising a knockdown framework having dovetailed connections and binding-screws to retain same, combined with a detachable strip to which the framework is hinged, thumb-screws for attaching the strip to a door, removable trousers-supporting bars and the presser-board, substantially as shown and described.

60

4. In a device for pressing trousers, the combination with a knockdown frame having dovetailed connections, the strip hinged to the framework, and designed to be attached to a door, of a series of rounds passed through apertures in the side strip of the framework with their inner ends seated in depressions in the opposite side strip, and pivoted spring retaining members designed to be held over the outer ends of the rounds, and means for holding the frame in a vertical position, substantially as shown and described.

75

In testimony whereof we affix our signatures in presence of two witnesses.

NATHANIEL TYLER, JR.
WILLIAM A. LIEBER.
